UNITED STATES PATENT OFFICE.

EDGAR C. PEIXOTTO, OF AUGUSTA, GEORGIA.

DESIGN FOR A SUPPORTING-BRACKET FOR TELEPHONE-RECEIVERS.

SPECIFICATION forming part of Design No. 33,780, dated December 25, 1900.

Application filed November 23, 1900. Serial No. 37,544. Term of patent 7 years.

To all whom it may concern:

Be it known that I, EDGAR C. PEIXOTTO, a citizen of the United States, residing at Augusta, in the county of Richmond and State of Georgia, have invented and produced a certain new and original Design for a Supporting-Bracket for Telephone-receivers, and I do declare the following to be a full, clear, and exact description of the invention, such as will enable others skilled in the art to which it appertains to make and use the same.

My invention relates to a design for a supporting-bracket for telephone-receivers, and is illustrated in the accompanying drawings, in which—

Figure 1 is a perspective view of the bracket. Fig. 2 is a side elevation of the same, showing one of the side walls of the slot broken away to expose the tongue; and Fig. 3 is a top plan view.

As shown in the drawings, the leading or material feature of my invention consists of

the curved bracket-arm 1, having at one end a transverse channeled rest or receptacle 2 and in the other end a slot 3, receiving a tongue 4 on a bracket-plate 5. This tongue is formed with a curved front edge 6 and a lower projecting lug 7.

8 is a pin passing through the tongue and walls of the slot 3, and 9 shoulders on the plate 5.

Having thus described my invention, what I claim is—

The design for a supporting-bracket for telephone-receivers, substantially as herein shown and described.

In testimony whereof I have hereunto set my hand in presence of two subscribing witnesses.

EDGAR C. PEIXOTTO.
